UNITED STATES PATENT OFFICE.

EUGÈNE SCHNEIDER, OF LE CREUZOT, FRANCE, ASSIGNOR TO SCHNEIDER & CIE., OF PARIS, FRANCE, A LIMITED JOINT STOCK COMPANY OF FRANCE.

SAFETY LOCKING APPARATUS FOR GUNS OF LARGE CALIBER.

1,310,884.

Specification of Letters Patent.

Patented July 22, 1919.

Application filed August 6, 1917. Serial No. 184,651.

To all whom it may concern:

Be it known that I, EUGÈNE SCHNEIDER, a citizen of the French Republic, residing at Le Creuzot, Saône-et-Loire, France, have invented a new and useful Improvement in Safety Locking Apparatus for Guns of Large Caliber, which is fully set forth in the following specification.

This invention has for its object to provide an improved locking apparatus for preventing the premature operation of the firing apparatus of a gun of large caliber during loading.

According to this invention the usual catch between the gun cradle and the elevating sectors, is utilized for operating a device for locking the firing apparatus. For this purpose the elements of the said catch that are respectively carried by the cradle and the elevating sectors, are arranged in such a manner as to release the mechanism that actuates the firing apparatus only after the catch has been closed, while inversely they lock the said mechanism by the mere fact of their being opened; this opening being capable of being effected mechanically or by hand when the breech of the gun barrel is raised for loading.

Two embodiments of this invention are illustrated by way of example in the accompanying drawings in which:

Figures 1 to 8 show the first embodiment.

Fig. 1 is a partial side elevation of a gun provided with the improved locking apparatus, the parts of the said apparatus being shown in position for firing, that is to say, in any position in which the firing apparatus is released.

Fig. 2 is a cross section on the line II—II of Fig. 1.

Figs. 3 and 4 are sections respectively on the lines III—III and IV—IV of Fig. 2.

Fig. 5 is an elevation corresponding to Fig. 1, showing the parts in the position they occupy during the loading of the gun.

Fig. 6 is a cross section on the line VI—VI of Fig. 5.

Figs. 7 and 8 are sections respectively on the lines VII—VII and VIII—VIII of Fig. 6.

Figs. 9 to 15 illustrate a modification.

Fig. 9 is a partial side elevation showing the parts in the normal or closed position of the catch between the gun cradle and the

elevating sectors, and of release of the firing apparatus.

Fig. 10 is a cross section on the line X—X of Fig. 9.

Fig. 11 is a similar view showing the parts in the open position of the catch between the cradle and the sectors, the firing apparatus being locked.

Fig. 12 is a vertical section on the line XIII—XII of Fig. 11.

Fig. 13 is a section on the line XIII—XIII of Fig. 10.

Figs. 14 and 15 are sections respectively on the lines XIV—XIV and XV—XV of Fig. 11.

Fig. 16 is an elevational view with parts broken away showing the manner of connecting shaft K and pinion N.

Fig. 17 is a plan view of Fig. 16.

Figs. 18, 19 and 20 are detail views on an enlarged scale, Fig. 19 being an enlarged horizontal sectional view on the line 19—19 of Fig. 16, Fig. 20 a similar view but showing the parts in a different position, and Fig. 18 a developed view of a cam surface provided on pulley P.

In the several figures, A is the gun barrel and B is the cradle or mount journaled in a carriage C. On the trunnions B¹ of the cradle are pivoted the elevating sectors D connected together by plating D¹ and adapted to be operated by any suitable known mechanism, such as E—E¹—E²—E³.

The firing apparatus proper may be of any suitable known type and may comprise for instance a hammer F fulcrumed on a fixed axis. In the example shown this hammer is assumed to be operable by means of a push rod G acting upon a lever F¹ fixed to the hammer, and guided in a bracket B² provided on the cradle B. The rod G is operable by means of a handle G¹.

The device for locking the mechanism for operating the firing apparatus during the loading of the gun, comprises essentially a locking bolt or a spring stop controlled by the catch between the cradle B and the sectors D.

In the embodiment of the invention shown in Figs. 1 to 8, the locking part proper consists of a rocking beam H—H¹ fulcrumed on a pin h carried by a bracket B³ formed on the cradle. A spring stud H² has a constant tendency to push the arm H¹ of the

rocking beam into a position for locking the rod G (Figs. 5 and 6) wherein it is located in the path of a nose *g* on the said rod. Normally, that is to say, when the gun is situated in any firing position, the arm H¹ of the rocking beam is caught by the catch between the cradle B and the elevating sectors D. In the example shown in Figs. 1 to 8, this catch comprises on the connecting plating D¹ between the sectors, a movable member I operable by hand or mechanically, so shaped as to present at the same time a nose *i* for engaging the nose *b* on the cradle, and a nose *i*¹ for engaging the rocking beam H—H¹. The member I is in reality a pusher guided by means of a sleeve I² against a stud I¹ fixed to the plating; an opposing spring being provided in the sleeve and adapted to bear at one end against the said stud, and at its other end against the inner end of the said sleeve.

The member I is assumed to be operated by hand means likewise carried by the plating D¹. This means comprises a link J jointed at one end to the pusher and preferably fast at the other end to a shaft K moving in collars *k* carried by the plating D¹. This shaft is rotated by hand by means of a crank handle L. A spring K¹ has a constant tendency to keep the said catch between the cradle and the sectors in position of engagement (Figs. 1 to 4); this position corresponding as already stated, to the position of release of the mechanism for operating the firing apparatus.

The shaft K is, on the other hand, in the normal position shown in Figs. 1 to 4, locked by means of a finger K² in a socket *m* formed in the sector M that is formed on or fixed to the cradle B and serves for raising the gun barrel into the position for loading.

When the parts are in the position shown in Figs. 1 to 4, and it be desired to load the gun, the catch between the cradle B and the sectors D is opened in the usual manner. But, according to this invention, this opening of the catch produces at the same time a locking of the firing apparatus. Therefore it will be understood that if the shaft K is actuated by turning the crank handle in the direction of the arrow shown in Fig. 4, the spring push member I will be moved from right to left. Consequently in disengaging the nose *i* from the nose *b* of the cradle, the nose *i*¹ will at the same time be moved away from the end of the arm H¹ of the rocking beam H—H¹. The action of the spring stud H² will cause the rocking beam H¹ to rock into the position shown in Figs. 5, 6 and 8, which has the result of bringing the free end of the arm H into the path of the nose *g* on the operating rod G—G¹ of the mechanism for operating the firing apparatus. By the rotation of the

shaft K, the finger K² has been disengaged from the socket *m* of the raising sector. During the raising operation, the sector M by rubbing against the finger K², prevents the opposing springs K¹ and I³ from coming into action.

When the loading has been effected, the raising sectors are actuated in the reverse direction so as to bring stops B⁴ formed on the cradle into contact with one of the elevating sectors D. These stops are so arranged that their coming into contact with the sectors D corresponds to the engagement of the finger K² in the socket *m* of the raising sector. This allows the opposing springs K¹ and I³ to come into action so as to return the parts of the catch and locking apparatus into the position shown in Figs. 1 to 4.

Instead of actuating the shaft K by hand by means of a crank handle L, it is obvious that the said shaft may be actuated by the means for actuating the raising mechanism, that is to say, it may be placed under the control of the pinion N which is actuated in the usual manner by gear, such as O—P—Q—R—S.

Referring to Figs. 16, 17, 18, 19 and 20, pinion N transmits its movement to shaft K as follows.

Pinion N is fast to a sleeve O which can slide in the hub *p* of sprocket wheel P connected by chain Q with sprocket wheel R keyed on the axle of hand-operated drive wheel S.

An arm K³ fast to shaft K and solid with locking finger K², which is adapted to engage in opening *m*, constantly engages in a groove *o* in hub O.

The hub O furthermore carries at its opposite end two fingers O¹ which bear on cam surfaces P¹ symmetrically formed on the interior wall of sprocket wheel P. A spring O² located in the hub O tends constantly to force pinion N into the position shown in Fig. 19. The teeth of pinion N are not as wide as those on sector M. The extension of the spring is only possible at the moment when finger K² is opposite opening *m*.

The rotation of shaft K and the simultaneous disengagement of finger K² from notch *m* result from the operation of cams P¹ on fingers O¹ of hub O fast to pinion N, which latter is immobilized by the fact that its teeth are in mesh with those of sector M stationary at this moment. On turning the wheel S, and thereby the transmission R—Q—P, the two symmetrical cams P¹ are rotated and the two fingers O¹ are elevated. They thus come into the position shown in Fig. 20 and actuate, through hub O, the arm K³ and finger K². By continuing to turn wheel S, fingers O¹ engage shoulders

p^1 formed at the summit of cams P^1 and in consequence pinion N is forced into movement from rotation of sprocket wheel P . The elevating sectors being held from movement by the vertical pointing mechanism, the pinion N elevates the sector M which glides in front of finger K^2 thus holding it out of engagement.

In the modification shown in Figs. 9 to 15, the member I has the form of a cock shaft working in the sides of the plating D^1 . The catch between the cradle B and the member I is formed by means of recessed members b engaging full portions i of the cock shaft I . A rotation of the member I through 180 degrees will bring recesses i^2 in shaft I opposite the recesses in members b thereby permitting shaft I to release cradle B . A cam i^1 formed on the member I , will normally raise a spring stop $H-H^2$ and thus give freedom of movement to the operating member G^1 of the actuating rod G^1-G of the mechanism for operating the firing apparatus.

It will be perceived that by disengaging finger K^2 from the socket m formed in the raising sector M , and at the same time operating the crank handle L and a chain gear $L^1-L^2-L^3$, a pinion I^4 fixed to the member I is actuated, whereby the member I is moved into the position shown in Figs. 11, 14 and 15. In this position the catch between the cradle B and the elevating sectors D is opened, at the same time as the spring push $H-H^2$ has moved with its upper end into the path of the nose g formed on the operating member G^1 of the rod G .

The gun in this modification is returned from loading to normal position in the same manner as in the construction shown in Figs. 1-8, by manual power applied through hand-wheel S , and transmission R, Q, P , and pinion N to sector M .

What I claim is:—

1. In safety apparatus for preventing the premature actuation of the firing means of guns during loading, the combination of a gun cradle provided with a gun having firing means, elevating sectors for said cradle and gun, and means for imparting relative movement between the cradle and sectors, a spring-pressed catch member carried by said sectors and adapted to engage said cradle to lock the same to the sectors for firing, manual means for operating said catch member, a spring-pressed safety member normally tending to move into the path

of said firing means to prevent its operation and adapted to be engaged by said catch member and held out of said path when the cradle and sectors are locked for firing and when released from said catch to move into said path, and automatic means for preventing the reengagement of said catch member and the safety member during the loading operation.

2. In safety apparatus for preventing the premature actuation of the firing means of guns during loading, the combination of a gun cradle provided with a gun having firing means, elevating sectors for said cradle and gun, and rack-and-pinion means for imparting relative movement of the cradle and sectors, a spring-pressed push rod on said sectors having locking engagement with said cradle, manual means for operating said rod, a spring-pressed safety member on said cradle normally tending to move into the path of said firing means to prevent its operation and adapted to be engaged by said push rod and held out of said path when said rod is in locking position for firing, and means for holding said push rod out of engagement with said safety member when said rod is out of locking position for loading of the gun.

3. In safety apparatus for preventing the premature actuation of the firing means of guns during loading, the combination of a gun cradle provided with a gun having firing means, elevating sectors for said cradle and gun, and means for imparting relative movement between the cradle and sectors, a spring-pressed catch member mounted on said sectors and adapted for locking engagement with said cradle for firing, a spring-pressed safety locking member normally tending to move into the path of said firing means to prevent operation of the latter, means operated by the cradle-moving means for operating said catch member whereby the latter may engage said safety member to move the latter out of said path for firing, and automatic means for preventing the operation of said catch means when said cradle and sectors are out of firing position.

In testimony whereof I have signed this specification in the presence of two subscribing witnesses.

EUGÈNE SCHNEIDER.
